CLOCK

James W. Childs, Washington, D. C.

Application June 3, 1934, Serial No. 33,377

4 Claims. (Cl. 52—50)

This invention relates to clocks and more particularly to a clock having an illuminated face, having for its object to provide a construction simple in parts and more efficient in operation than those heretofore proposed.

With these and other objects in view the invention resides in the novel details of construction and combinations of parts as will be disclosed more fully hereinafter and particularly pointed out in the claims.

Referring to the accompanying drawing forming a part of this specification and in which like numerals designate like parts in all the views,—

Fig. 1 is a front elevation of a clock to which this invention has been applied;

Fig. 2 is a detail in horizontal plan illustrating a part of the clockwork mechanism involving this invention;

Fig. 3 is a detail sectional view illustrating the connection between a rotating contact pin and a stationary commutator segment by means of which an electric circuit is maintained;

Fig. 4 is an elevational view of a pair of commutator segments;

Fig. 5 is a view illustrating the mounting of a clock hand on its rotating shaft; and

Fig. 6 is a detail horizontal section showing a modification of the mounting of electric circuit conductors on the shafts of the clock hands.

In the drawing a clock is generally indicated by the numeral 1 provided with the dial 2 over which the hour-hand 3 and the minute-hand 4 are adapted to pass, the minutes hand being mounted on the outer end of a tubular shaft 5, and the hour-hand being mounted on the outer end of the shaft 6 passing through said tubular shaft. The shaft 6 has mounted thereon the gear 7 driven by a pinion 8 mounted upon a shaft 9 of the clockwork train, and the shaft 5 has mounted thereon the gear 10 driven by a pinion 11 mounted on the shaft 12 of another portion of the clockwork train, whereby said gears will be rotated as readily understood in horology from a suitable motor source of power, not shown, to give the proper timed rotation of the hour- and minute-hands.

The inner shaft 6 as shown in Fig. 5, as also the tubular shaft 5, may each be made of electrical non-conducting material, the inner shaft 5 having spaced longitudinally extending grooves formed in its surface to receive therein the current conducting wires 12 and 13, the outer end of each of these wires being soldered or otherwise rigidly connected to an electrical conducting plate 55 adapted to be slidingly engaged by electrical con-

ducting spring fingers extending from one of the hands of the clock.

The gear 7 has rigidly attached to one face thereof an electrical non-conducting cup or socket 15 provided with an opening 16 in the side wall thereof near its base and through which the inner end of the wire such as 13 may pass and be soldered or otherwise suitably connected to a coil spring 17 adapted to press outwardly from the cup a metallic contact pin 18 having a free 10 sliding fit within the cup. A companion and similar cup 19 is disposed on the same face of the gear 7 but substantially diametrically opposed to the cup 15, the cup 19 also carrying a freely slideable metallic contact pin 20 similarly spring 15 pressed and electrically connected to the wire 12.

The frame of the clock, not shown for the purpose of clearness, carries two substantially diametrically opposed brackets 25 and 26 each extending inwardly toward the axis of the shaft 6 and upon the inner ends of said brackets is rigidly secured an electrical non-conducting ring 27 surrounding the shaft 6. Upon the side of this ring facing the gear 7 is mounted a pair of substantially semi-circular metallic commutator segments 28 and 29, said segments being concentric with the shaft 6 and secured to the ring as by the bolts 30 passing through said ring and threaded into said segments without penetrating the exposed surface of said segments, wherefore the exposed surface is left unmarred for sliding contact with the pins 18 and 20 during their circular travel with the gear 7. The ends of the commutator segments do not touch each other, being spaced apart as at 31 a distance which is slightly greater than the diameter of said contact pins so that no pin is capable of spanning the ends of said segments and forming an electrical path therebetween. To provide a continuous contact surface for said pins, the ring 27 is formed with 35 projections or lugs to fill the space between the segment ends at 31. The segments 28 and 29 are electrically connected as by the wires 32 and 33 respectively to a source of electric power.

The gear 10 has secured to one face thereof a pair of electrical non-conducting cups 35 and 36 carrying the metallic spring-pressed contact pins 37 and 38 respectively which are substantial duplicates in all respects to the cups 15 and 19 and contact pins 18 and 20 associated with the gear 7. Also there is a second pair of brackets 39 and 40 carried by the clock framework for supporting another electrical non-conducting annular ring 41 concentrically surrounding the tubular shaft 5 and in all respects a duplicate of the 45

ring 27. To this second ring 41 is secured a pair of electrical conducting commutator segments 42 and 43 which are duplicates of the segments 28 and 29 and are connected to the wires 32 and 33 as by the electric current conductors 44 and 45 respectively.

The tubular shaft 5 carries the wires 46 and 47 for electrically connecting the contact pins 38 and 37 respectively with similar metallic plates 10 such as 55 at the outer end of said shaft for contactingly supporting the other hand of the clock.

Each hand of the clock is made in the form of an incandescent electric light bulb 50 as best illustrated in Fig. 5, the bulb portion being preferably oval or flat in cross-section so as to occupy the least possible space between the dial 2 and the glass front of the clock. The base of each bulb is bifurcated as at 51 and carries the ends of the looped filament 52. The ends of the filament are connected to metallic fingers such as 53 and 54 formed in continuation of the bifurcated ends of the bulb and disposed in parallel relation to each other. The metallic plates such as 55, carried by each hand rotating shaft, are rigidly secured or firmly pressed in kerfs such as 56 disposed on the end of each shaft so that the fingers 53 and 54 of each bulb may readily be slid transversely of a shaft into surface contact with said plates, and to further aid in the securement of said fingers to said plates, a locking depression such as indicated at 57 may be provided. In other words, from Fig. 5 it will be seen that the wires 46 and 47 are connected to duplicate plates such as 55 disposed substantially diametrically of the shaft 5, and from Figs. 5 and 6 it will be understood that the other wires 12 and 13 are likewise connected to plates which are duplicates of the plates 55 but disposed in similar kerfs on the other shaft 6. Therefore it will be seen that a simple and quick push-pull connection is afforded between each bulb hand and its shaft whereby a hand may be readily placed in or removed from position on its shaft.

In the construction shown in Fig. 6 the tubular shaft 5 and the inner shaft 6 are illustrated as made of metal or electrical conducting material, and in this case it will of course be necessary to insulate the wires 12, 13, 46 and 47 as indicated at 60, and it will also be necessary to insulate the bulb fingers 53 as well as their metallic contact plates such as by disposing them in troughs of insulation as indicated at 61, but otherwise the construction is similar to that above described and shown in Fig. 5.

From the foregoing description it will therefore be seen that electric current from a suitable source will flow over the wire 32, energizing commutator segment 28 and from which the current will pass through the contact pin 18 to and through its spring 17 and pass over the wire 13 to and through the filament of the lamp hand carried by the shaft 6, thence over the wire 12 to and through the contact pin 20 and the other commutator segment 29 to the wire 33 and back to source, illuminating said bulb hand. At the same time a branch circuit will permit the current to pass over the wire 44 to energize commutator segment 42 from which the current will pass through the pin 37, over the wire 47 and through the bulb hand carried by the other shaft 5, said current returning over the wire 46 through the pin 38 and other commutator segment 43 to the wire 45 and thence back to source, illuminating the second bulb hand. If desired a switch may be interposed in the main current conductors

whereby the illumination of the hands may be controlled, and in such case it will be found convenient to tint with coloring matter the glass of the bulbs constituting the hands of the clock so that they may be seen more readily when not illuminated, in contrast to the dial. Because of the gap, between the ends of the commutator segments, there will be a break in the circuit when each of the contact pins reaches said gap but this break will be of very short time duration since the gap is made only slightly greater in dimension than the diameter of the contact pin, occurring once every thirty minutes with respect to the minute-hand and once every six hours with respect to the hour-hand.

From the foregoing description it will therefore be seen that by this invention there is provided a clock having a rotatable gear and a shaft rotated by said gear, said shaft having disposed therein a pair of electric current conductors, the gear having mounted thereon and extending from the face thereof, a pair of longitudinally yieldable brushes or pins which are individually connected to said conductors. There is also provided a stationary ring of insulating material surrounding said shaft with a pair of commutator segments mounted on the face of said ring next to said gear and contacting said pins, with the space between the segment ends filled with the material of said ring to provide a continuous surface over which said pins will travel, said segments being concentrically disposed with respect to said gear and shaft and connected to a source of electric current. Contact plates are disposed on opposite sides of the outer end of said shaft and connected to said conductors, and a hand is provided comprising an electric light bulb having spaced filament terminals slidingly and springingly engaging said plates for holding said bulb to said shaft.

It is obvious that those skilled in the art may vary the details of construction and arrangements of parts without departing from the spirit of this invention and therefore it is desired not to be limited exactly to the foregoing disclosure except as may be required by the claims.

What is claimed is:

1. In a clock the combination of a rotatable gear; a shaft rotated by said gear and carrying a pair of electric current conductors; a pair of substantially semi-circular stationary commutator segments concentrically disposed with respect to said gear; means to electrically energize said segments; a pair of brushes carried by said gear and engageable with said segments one at a time; contact plates disposed on opposite sides of the outer end of said shaft and connected to said conductors, and a hand comprising an incandescent electric light bulb having spaced filament terminals slidingly engaging said plates for holding said bulb to said shaft.

2. In a clock the combination of a rotatable gear; a shaft rotated by said gear and having disposed therein a pair of electric current conductors; a pair of longitudinally yieldable pins mounted on and extending from a face of said gear and individually connected to said conductors; a stationary ring of insulating material surrounding said shaft; a pair of commutator segments mounted on the face of said ring next to said gear and contacting said pins, the space between the segment ends being filled with the material of said ring to provide a continuous surface over which said pins will travel, said segments connected to a source of electric current;

5 contact plates disposed on opposite sides of the outer end of said shaft and connected to said conductors; and a hand comprising an electric light bulb having spaced filament terminals slid-
ingly engaging said plates for holding said bulb to said shaft.

3. In a clock the combination of a shaft hav-
ing a pair of diametrically disposed recesses formed therein; a contact plate disposed in each
10 recess; a hand comprising an incandescent elec-
tric light bulb having spaced filament terminals slidably engaging said plates for holding said bulb to said shaft; and electric current conductors se-

cured to said plates and extending within said shaft for illuminating said bulb.

4. In a clock the combination of a shaft hav-
ing a pair of kerfs formed diametrically at one end thereof; a contact plate rigidly mounted in each kerf; a hand comprising an incandescent electric light bulb having a bifurcated base to accommodate the shaft, and filament terminals springingly engaging said plates for holding said bulb to said shaft; and electric current conduc- 10
tors secured to said plates and extending within said shaft for illuminating said bulb.
